COMBINATION RADIO RECEIVER
AND CLOCK

Herbert J. Zeller, Chicago, Ill., assignor to Motorola, Inc., Chicago, Ill., a corporation of Illinois

Application November 14, 1950, Serial No. 12,965

Term of patent 14 years

(Cl. D56—4)

To all whom it may concern:

Be it known that I, Herbert J. Zeller, a citizen of the United States, residing at 4545 Augusta Boulevard, Chicago, State of Illinois, have invented a new, original, and ornamental Design for a Combination Radio Receiver and Clock, of which the following is a specification, reference being had to the accompanying drawing, forming a part thereof in which:

Fig. 1 is a front elevational view of the combination radio receiver and clock, embodying my new design;

Fig. 2 is a top plan view of the same; and

Fig. 3 is an end elevational view thereof.

I claim:

The ornamental design for a combination radio receiver and clock, substantially as shown.

HERBERT J. ZELLER.
